UNITED STATES PATENT OFFICE

ALEXIS F. GILLET, OF OMAHA, NEBRASKA

DESIGN FOR A CALENDAR

Application filed January 10, 1931. Serial No. 38,264. Term of patent 3½ years.

To all whom it may concern:

Be it known that I, ALEXIS F. GILLET, a citizen of the United States of America, and a resident of Omaha, in the county of Douglas and State of Nebraska, have invented a new, original, and ornamental Design for Calendar, of which the following is a specification, reference being had to the accompanying drawings, forming part thereof.

Figure 1 is a plan view of a calendar.

Figure 2 is a top plan view of the calendar shown in Figure 1, and

Figure 3 is an enlarged transverse section, the view being taken substantially along the dotted line 3—3 of Figure 1.

I claim:

The ornamental design for a calendar as shown.

ALEXIS F. GILLET.
